UNITED STATES PATENT OFFICE

WILLIAM J. REHRIG, OF LOS ANGELES, CALIFORNIA

MACHINE FOR MAKING COAT HANGERS

Application filed July 30, 1930. Serial No. 471,743.

This invention is intended to provide means for automatically rounding or trimming the top or convex edges of coat hanger blanks and also for boring holes through said blanks for the usual supporting hooks. More particularly the primary object is to provide means which will produce this work quickly and effectively, whereby a maximum number of coat hangers are manufactured with a minimum of hand labor and expense. It has heretofore been customary to do this work by a series of hand and machine operations, whereas by the use of my invention a single operation of feeding the coat hanger blanks to the machine is only required, the machine being adapted to perform the functions above indicated, rapidly and entirely automatically, the finished articles being ejected clear of the machine. It is customary, because of expense, to construct coat hangers out of wood, the blanks being cut on a curve with the grain running towards both ends. In order to trim the top or convex edges smoothly it is necessary to cut the material with the grain towards both ends. This function also is accomplished by my invention in an efficient and effective manner, whereby a smoothly finished article is produced.

In the accompanying drawings forming part of this specification, Fig. 1 is a side elevation of my invention, partly in vertical section taken on line 1—1 of Fig. 2; Fig. 2 is a plan of the entire machine; Fig. 3 is a perspective view of one of the coat hanger blanks before it has been trimmed and drilled; Fig. 4 is another perspective view of the coat hanger blank after it has been trimmed and partly broken away to show the hole which has been drilled for the usual hook; Fig. 5 is a plan of a detail with part of the structure broken away, showing one of the coat hanger blanks being trimmed and drilled; Fig. 6 is a section of a detail taken on the line 1—1 of Fig. 2, showing one of the clamping units for holding the blank on the turn table, the clamp being in released position immediately before a blank is placed on the table to be trimmed and drilled and the trimmers not being shown;

Fig. 7 is a section taken on the line 7—7 of Fig. 1, part of the turn table being broken away and the frame of the machine removed; Fig. 8 is an enlarged section of a detail taken approximately on line 7—7 of Fig. 1 showing one of the spring ejectors; and Fig. 9 is an elevation of the structure shown in Fig. 8.

A indicates a skeleton frame which may be of any suitable construction to support the parts of the machine. B is a vertical stationary shaft centrally disposed from top to bottom of the frame and upon which a horizontal turn table C is journaled, said turn table being provided with a sleeve 10 and revolved continuously by a bevel gear 11 or any other suitable prime mover. The turn table has a peripheral horizontal rim 12, constituting a circular rest which revolves about shaft B as an axis in a horizontal plane and is adapted to carry the coat hanger blanks D flat upon their sides while their rims 13 are being trimmed or rounded and their median portions are being drilled and formed with hook receiving holes as shown at 14 in Fig. 4. This circular rest 12 conforms substantially with the longitudinal curvature of the coat hanger blanks and in width is less than the dimensions between the convex and concave edges of each blank. It is adapted to receive and carry a series of said blanks during the complete cycle of operation of the machine, that is from the time of placing the blanks in a hopper like structure G above said rest 12 until the blanks are successively ejected or kicked off after the trimming and drilling operations.

The circumference of the rest is sufficient to accommodate any desired number of coat hanger blanks when arranged lengthwise and flat thereon. As shown the rest will hold five blanks evenly spaced apart. For each blank the turn table is provided with a pair of clamps E for holding the corresponding blank on the rest and with a drill element F for drilling the hole 14 through the blank while the turn table is revolving. Also for all of the blanks two trimmers H are arranged to trim and finish the convex edges. These operations are automatic, no hand labor being required after the blanks have been

placed in the hopper and until after they have been finished and ejected from the machine.

The hopper structure consists of two pairs of vertical angle members 15 and 16, the two pairs being secured to the frame A and forming a pair of vertical channels adapted to receive the end of a stack of blanks D arranged flatwise upon each other and curved outwardly corresponding with the curvature of the rest. Two segmental guards 17 and 18 are secured to the lower ends of the angle members 15 and 16 to form a longitudinal channel for the lowermost blank below the stack of blanks. The inner surface of the rest has a series of ejector springs 19, there being a pair for each blank against its inner edge on the rest 12 and these ejectors are sprung back by contact against the inner segmental guard 17 as the turn table revolves in the direction of the arrow (Fig. 2) but engage and tend to press said blank outwardly away from the rest and table as soon as the lowermost blank moves forwardly from below the stack. The outermost guard 18 continues to hold the blank on the rest while the corresponding pair of clamps E engage the blank on the rest previous to contact with the trimmers H and corresponding drill F. As the turn table revolves as stated one of the five evenly spaced shoulder members 20 on the surface of the rest engages the lowermost blank D of the stack in the hopper and serves to slide it from below the stack and cause it to move with the turn table during the remaining portion of a revolution until released and ejected from the machine.

Each pair of clamp members E for holding a blank on the rest is operated to engage or release a blank by a cam 21 (Fig. 7), on the main shaft B, having a suitably shaped cam groove 22. Each member of each pair of clamps E consists of a spring urged presser foot 23, (see Fig. 1) which is carried by a swinging arm 24, said arm extending down through the turn table and being pivoted through a cam groove 25 by the pin or pivot 26. The movement of the presser foot 23 is outward and down upon the blank to hold the latter on the rest and upward and back away from over the rest. This movement is imparted to said arm by a crank 27 (see Fig. 6) which in turn is tiltingly mounted on a shaft 28, said shaft being coupled to operate both clamp elements of a pair simultaneously. Rocking movement is imparted to said shaft by a single slide 30 in a guide block 31 which is secured to the table by bolts 32, said slide being coupled to said shaft 28 by the crank arm 33 and coupling link 34 and being connected with the cam 21 in its cam groove by the roller pin 35.

Thus immediately following the removal of a blank from below the stack of blanks in the hopper, the corresponding pair of clamps

is forced down against said blank to hold the latter firmly upon the rest with its convex edge projecting outwardly from the table.

In this condition the turn table revolves the blank into co-action with the trimmers H. These trimmers are arranged to cut the coat hanger blanks with the grain of the wood, that is towards both ends, the first trimming element carrying a rotating cutter 36 revolving in the direction of its arrow shown in Fig. 5 or counterclockwise and the second trimming element carrying a rotating cutter 37 revolving in the direction of its arrow or clockwise. The rotating cutter 36 is driven by an electric motor 38 which is mounted in a carriage 39, said carriage being pivotally mounted at 40 in the main frame A to swing in a horizontal plane with the periphery of the cutter 36 in contact with the convex edge of the blank. A coil spring 41' on rod 42 is pivotally secured at one end by pivot 42' to the main frame and slides through a holder 43, thus serving to swing the carriage 39 and urge the cutter 36 in cutting action against the blank. A nut 44 on the outer end of rod 42 acts as a stop against said holder to adjustably limit the depth of cutting. The outer wall of the rim 12 has a circumferential series of cams 41, there being one properly positioned for each blank carried by the turn table, and the carriage 39 has a cam operated lifting arm 46 which serves to co-act with each cam 41 and lift the cutter 36 out of contact with the forward portion of each blank and allow the cutter to perform its cutting action only with the grain of the wood on the last half or latter portion of the blank. The cutter 37 likewise is revolved by an electric motor 47 which is mounted in a carriage 48, said carriage being pivotally mounted at 49 in the main frame A to swing in a horizontal plane with the periphery of the cutter 37 in contact with the outer edge of the blank. A spring 50 held on a rod 51 which slides through a holder 52 serves to swing the carriage 48 and urge the cutter 37 in cutting action against the blank and the nut 53 acts as an adjustable stop against said holder to limit the depth of cutting. There is no cam operated lifting element for this cutting element, the action of the cutter being to cut the forward portion of the convex edge of the blank with the grain of the material and to follow freely without cutting when passing over the last portion or previously cut portion of the blank. From then on the blank remains clamped on the rest until it is drilled, whereupon it is ejected automatically.

Assembled on the turn table are the drill elements F, there being five in number, one for each blank upon the rest. Each drill element has an electric motor 54, receiving current through a commutator 55 on the shaft B and being continuously operated to revolve a drill 56 while the turn table revolves. Each

motor is mounted upon a sliding base 57 which is carried by the turn table and permits the motor to reciprocate its revolving drill radially from the shaft B and back to drill a hole through a blank as shown in Fig. 4 while the turn table makes a complete rotation. The various slides are actuated by a cam 58 having a cam groove 59 so shaped as to co-act with cam rods 60 connected with the motor bases 57 to move each drill into and out of a blank as the turn table revolves and to completely drill the blanks before reaching a position immediately ahead of the hopper G, whereupon the cam 21 releases the clamps and the spring ejectors 19 eject the blank from the machine. The cutting by drills commences upon a blank while the latter is in a position at the lower end of the hopper G and while the cutters 36 and 37 are performing their functions, each drill being driven through a blank and withdrawn while the turn table moves each blank from a position immediately after leaving the hopper G until reaching a position immediately before returning to the hopper and when the finished blank is released and ejected from the turn table. One drill only acts upon a blank and a plurality of blanks being operated upon at a time in the machine to increase speed of production.

This cycle of operations continues rapidly and continuously without stopping, the clamping, trimming, boring and ejecting actions occurring without interruption and not step by step, thus adapting the machine for high speed production with a minimum of hand labor and expense. The period of time required for boring while the turn table operates at high speed requires a plurality of boring instrumentalities and sufficient space circumferentially to hold a series of blanks on the turn table in order that the boring function can be accomplished in an efficient manner while the turn table revolves continuously without pausing.

In accordance with the patent statutes, I have described the principles of operation of my invention together with the construction which I now consider to represent the best embodiment thereof, but I desire to have it understood that the structure shown is only illustrative and that the invention can be carried out by other means and applied to uses other than those above set forth within the scope of the following claims.

Having described my invention what I claim as new and desire to secure by Letters Patent is:

1. A machine for trimming the convex rims of garment hanger blanks, comprising, in combination, a continuously revoluble carrier, means for feeding a series of said blanks to be trimmed lengthwise in a circular path upon said carrier with their convex rims coincident with the axis of said carrier, means for holding said blanks on said carrier

when received thereon and for releasing said blanks near the end of their cycle of travel, means for trimming the convex rims of said blanks while the blanks are held upon said carrier, a plurality of power drills movable continuously with the carrier, one drill being provided to drill a hole in each blank of said series while the blanks are being advanced by said carrier, and means for ejecting said blanks from the carrier near the end of their cycle of travel.

2. A machine for trimming the convex rims of garment hanger blanks, comprising, in combination, a carrier continuously revoluble about a substantially vertical axis, means for revolving said carrier, hopper means for holding a stack of said blanks over the outer portion of the surface of said carrier, means carried on said carrier for successively removing the lowermost blanks of said stack to distribute them longitudinally at spaced intervals around said carrier and with their convex rims coincident with the axis of said carrier, means for automatically clamping the individual blanks on said carrier after they are removed from said stack and during part of the cycle of the carrier and releasing the blanks near the end of their travel, means for trimming the convex edges of the individual blanks on the carrier, a plurality of power drills movable continuously with the carrier, one drill being provided to drill a hole in each blank of said series while the blanks are being advanced by said carrier, and means for ejecting the blanks when they are released from the carrier.

3. A machine for trimming wooden garment hanger blanks having convex rims with the grain of the wood trending longitudinally towards the opposite ends, comprising, in combination, a carrier continuously revoluble about an axis, means for revolving said carrier, means for feeding a series of said blanks to be trimmed lengthwise in a circular path upon said carrier with their convex rims coincident with the axis of said carrier, means for holding said blanks on said carrier when received thereon and for releasing said blanks near the end of their cycle of travel, means for trimming the convex rims of said blanks while the blanks are held upon said carrier and revolved in a forward direction, said trimming means having a pair of cutting elements, the first revolving in a forward direction and disposed to trim the forward portion of the rim with the grain of a blank and the second revolving in the opposite direction and disposed to escape cutting said forward portion and to trim the latter portion of the rim with the grain of said blank, means for operating said second cutter to perform its function, a plurality of power drills movable continuously with the carrier, one drill being provided to drill a hole in each blank of said series while the blanks are being advanced by

125

130

135

140

said carrier, and means for ejecting the blanks from the carrier near the end of their cycle of travel.

4. A machine for working wooden garment hanger blanks having convex rims extending between their ends and the grain of the material trending longitudinally towards the ends of each blank, means for holding and continuously moving a series of the blanks 10 in a direction coincident with their rims when the blanks are arranged longitudinally in a circle, a pair of cutters, one being disposed to trim the forward portion and the other the latter portion of each rim while the blanks 15 are being moved in a forward direction, said cutters being revoluble to trim the material with the grain of said material in opposite directions a plurality of power drills movable continuously with the holding and moving 20 means, one drill being provided to drill a hole in each blank of said series while the blanks are being advanced.

5. A machine for working wooden garment hanger blanks having convex rims with 25 the grain of the wood trending towards the opposite ends, comprising, in combination, a circular carrier continuously revoluble about a vertical axis, means for revolving said carrier, means for holding a stack of blanks to 30 be fed down upon said carrier with their sides disposed horizontally and with their rims coincident with said axis, means actuated by the carrier for distributing a series of said blanks from the lower portion of said 35 stack at spaced intervals around the surface of said carrier with their convex rims projecting from the rim of said carrier, means for clamping each blank of said series upon said carrier, a pair of rotary cutters disposed to 40 trim the convex edge of each blank of said series while being held upon said carrier, the forward of said cutters revolving to cut with the grain of the forward portion of said convex edge of said blank and the rearward cutters 45 revolving in the opposite direction to cut with the grain of the rearward portion of said convex edge of said blank, means for holding said rearward cutter out of cutting action with the forward portion 50 of said rim and for moving and holding it in cutting action with said rearward portion of said rim as said carrier revolves, a plurality of power drills movable continuously with the carrier, one drill being provided to drill 55 a hole in each blank of said series while the blanks are being advanced by said carrier, and means for ejecting the blanks from the carrier after the cutters have performed their function.

60 6. A machine for working wooden garment hanger blanks having convex rims extending between their ends and the grain of the material trending longitudinally towards the ends of each blank, means for holding and moving a series of the blanks continuously in

a direction coincident with said convex rims, a pair of cutters one being disposed to trim the forward portion and the other the latter portion of each rim while the blanks are being turned in a forward direction, said cutters being revoluble to trim the material with the grain of said material in opposite directions, a plurality of power drills movable continuously with the holding and moving means, one drill being provided to drill a hole in each blank of said series while the blanks are being advanced, and means for releasing and ejecting the blanks after the drilling.

7. A machine for making garment hanger blanks having convex rims, comprising, in combination, a circular carrier revoluble about a vertical axis, means for revolving said carrier continuously, means for holding a stack of blanks to be fed down upon said carrier with their sides disposed horizontally and with their rims coincident with said axis, means actuated by the carrier for distributing a series of said blanks from the lower portion of said stack at spaced intervals around the surface of said carrier with their convex rims projecting from the rim of said carrier, means for holding each blank of said series upon said carrier, means for trimming the convex edge of each blank of said series while being held upon said carrier, a plurality of individual motor actuated drills revoluble with said carrier one drill being provided to drill a hole in each blank of said series, means for feeding each drill to drill a hole and withdrawing it from its work during a portion of the cycle of said carrier and means for ejecting the blanks from the carrier after said trimming and drilling operations.

In witness whereof I have signed my name to this specification.

WILLIAM J. REHRIG.
